Attorney

UNITED STATES PATENT OFFICE

IRENE E. LEDGER, OF LAKE GENEVA, WISCONSIN

PORTABLE TOILET

Application filed July 24, 1929. Serial No. 380,665.

This invention relates to new and useful improvements in toilet devices, and particularly to portable toilets.

One object of the invention is to provide a simple and inexpensive device, which may be conveniently carried in an automobile, and which is especially adapted for children's use.

Another object is to provide a device of this character which is adapted to be collapsed into a small compact form, whereby to occupy the minimum space in the automobile.

Another object is to provide a device of this character which is adapted to be extended for the purpose of providing the proper height for use by a child.

Other objects and advantages will be apparent from the following description when taken in connection with the accompanying drawing.

In the drawing:

Figure 1 is a vertical sectional view through a toilet made in accordance with the present invention, in collapsed condition, and supported on its bracket.

Figure 2 is a horizontal sectional view on the line 2—2 of Figure 1.

Figure 3 is a side elevation of the toilet, in extended position.

Referring particularly to the accompanying drawing, 10 represents a metal band or ring, of suitable diameter and height, which forms the base member of the device. Formed vertically in the band or ring 10, at regularly spaced intervals, are the elongated slots 11, each end having a horizontal slot portion 12, which extends in a direction opposite to that of the other end, as clearly shown in the drawing. Handles 13 are mounted on diametric sides of the ring 10, for manipulation of the ring, as will be explained later herein.

Disposed within the ring 10, for rotary movement, and for vertical slidable movement, is a cylindrical receptacle 14, said receptacle having its upper end, or mouth, threaded to receive the threaded lid or cover 15, which cover is provided with a handle 16 on its upper face. Mounted on the lower portion of the sides of the receptacle 14, at regu-

larly spaced intervals, and being of a number equal to the number of slots 11, of the ring 10, are the headed members 17, which are disposed in said slots and arranged to slide therein, as will be explained later.

Normally, when the device is not in use, the receptacle 14 is disposed wholly within the ring 10, with its headed members 17 lying within the lower horizontal end portions 12, of the slots 11, whereby said receptacle and ring are incapable of longitudinal sliding movement with relation to each other, and with the lid or cover 15 properly screwed into the upper end of the receptacle. When the device is to be used, the operator rotates the ring 10 and the receptacle 14 in opposite directions, to a sufficient extent to bring the headed members 17 into the lower ends of the vertical slots 11. The operator then slides the receptacle and ring longitudinally, with respect to each other until the headed members 17 are opposite the upper horizontal slot portions 12, after which he rotates the receptacle and ring, with respect to each other, to dispose the headed members in said upper slot portions. The receptacle 14 is then properly supported at the desired height, so that the child may sit upon the open upper end of the receptacle. After use of the device, the operator turns the receptacle and pushes the same down into the ring, and again gives the receptacle a partial rotation to lock the said receptacle and ring in collapsed condition. The lid is then screwed into the open end of the receptacle, and the device stored in some part of the automobile, until such time as the receptacle can be emptied and cleaned.

To provide means for storing the device in a place which will not inconvenience any of the occupants of the automobile, I secure to the dashboard, an angular U-shaped bracket 18, the arms of which extend horizontally rearward therefrom. A band clamp 19, comprising two sections pivotally connected together, has the pivoted portion thereof connected to one of the arms of the bracket 18, said clamp being engaged around the receptacle, as shown. One end of the band is provided with a pivoted bolt 20 which is ar-

ranged to be engaged in a kerf 21 in the other end of the band, and a nut 22 engaged thereon, for the purpose of properly clamping the band around the receptacle. The end of the band which carries the bolt 20 is extended rearwardly along the adjacent portion of band, and slightly spaced therefrom, as shown at 23, such portion having a boss 24 projecting from its inner face. The free end of the other arm of the bracket is provided with a similar boss 25, and when the band is swung inwardly into a position within or between the arms of the said bracket, the said arm end passes between the band and the end portion 23, so that the boss 24 snaps into the recess 26, formed by the boss 25, on the opposite face of said bracket arm, whereby to hold the band against movement. When the receptacle is properly clamped within the band, 10 and the band swung inwardly between the arms of the said bracket, the receptacle will lie between the instrument-board, and the dashboard, of the automobile, thereby not interfering with the person occupying the seat thereby.

By loosening the nut 22, and swinging the bolt out of the kerf 21, the band sections may be spread apart, and the receptacle released for use. After use the receptacle is 15 clamped within the band, and swung out of the way, as previously explained.

What is claimed is:

1. A portable toilet comprising a support, a receptacle telescoped therein, and means for maintaining the receptacle at different longitudinal positions within the support.
2. A portable toilet comprising a support, a rotatable and slidably receptacle telescoped within the support, and slidable connections 20 between the receptacle and said support whereby said receptacle may be held wholly within the support, at times, and in partly projecting position therefrom, at times.
3. A portable toilet comprising a receptacle, projections on the receptacle, and a support for the receptacle comprising a ring slidably receiving the receptacle therein having bayonet slots receiving said projections, whereby the receptacle is capable of being 25 held in different telescoped positions within the ring.
4. A portable toilet comprising a receptacle, a ring telescoped on the receptacle having vertical slots with lateral terminal slot 30 portions, and headed projections on the receptacle engaged in said slots, whereby the receptacle and ring are capable of movement relative to each other to provide an extension support for the receptacle.

60 In testimony whereof, I affix my signature.

IRENE E. LEDGER.
